[57] CLAIM

The ornamental design for a switchboard console for a telecommunications system, as shown and described.

DESCRIPTION

FIG. 1 is a top plan view of a switchboard console for a telecommunications system, showing my new design; FIG. 2 is a rear elevation view thereof;

FIG. 3 is an end elevation view thereof;

FIG. 4 is an elevation view as seen from the opposite end; and

FIG. 5 is a bottom plan view thereof.

The fragmentary broken lines representing the telephone cord are shown for illustrative purposes only.
